SPRAYING NOZZLE

Nathaniel W. Meloon, Buffalo, N. Y.

Application May 12, 1931. Serial No. 536,812

6 Claims. (Cl. 299—114)

This invention relates to improvements in spraying nozzles adapted for use as sprinklers, fountains, or for spraying liquid insecticide; in fact, for any purpose where a whirling or rotating discharge of liquid is desired in spray form, issuing from the nozzle under pressure.

One of the objects of my invention is the provision of a simple and inexpensive spraying nozzle, so designed that greater projection is assured under a given pressure than now attained by nozzles designed for similar purposes.

Another object of my invention is the provision of a spraying nozzle, by the use of which a greater projection of the spray is assured and a wider area covered thereby under lower pressure than ordinarily required; this being particularly desirable in places where the pressures of water is below the average, as it will be possible, under such conditions, to effectively spray lawns, or trees and shrubs, even though pressure below that usually considered effective, may be employed.

Another object of my invention is the provision of a spraying device having comparatively few parts, and wherein a spraying head is provided with a tapped hole for connection thereto of a pipe or hose, and further, wherein the parts are assembled by insertion one within the other through said tapped hole.

Another object of my invention is the provision of a spraying nozzle wherein a swirler element is removably confined within a sprayer head, yet serves to effect a rotary or swirling motion of the liquid entering the same under pressure.

A further object of my invention is to provide a spraying device with a non-rotatable swirler chamber surrounded by space and having peripheral ports through which the liquid enters the chamber under pressure tangentially to the inner surface of the wall of the chamber.

A further object is the provision of a spraying nozzle having a head in which a cylindrical chamber is fixedly secured and arranged to provide a space around at least a portion of the same, and wherein said chamber is provided with a peripheral port having course-directing walls tending to cause the liquid passing through said port to enter the chamber tangentially to the inner surface of the cylindrical wall of said chamber and thereby impart rotation or swirling motion to the liquid within said chamber at a velocity equaling that of the liquid entering through said port.

A further object of my invention is the provision of a spraying nozzle in which a swirler

chamber is provided having a ported wall arranged to offer minimum resistance to the passage of liquid passing therethrough and the area within said chamber equaling, or substantially equaling, that of the port or ports of said wall so as to cause the liquid to take a circular and component outward course in its passage through said chamber; in other words, a spiral course at a speed equaling that of the liquid entering said chamber; thus assuring greater projection of the spray from the nozzle and/or greater spread to assure coverage of a wider area.

A further object of my invention is the provision of a spraying nozzle constructed to assure greater projection and spread of the liquid over a greater area; also rotation or swirling action of the liquid passing through the spraying nozzle at a greater velocity than spraying nozzles now in use operating under like pressure.

A still further object of my invention is the provision of a spraying nozzle having a cylindrical chamber provided with a peripheral wall surrounded by space through which water is passed, said peripheral wall having a port, and preferably a plurality of ports, provided with inwardly-disposed and upwardly-inclined liquid-directing walls against which the liquid passing through said ports from said surrounding space is caused to enter said chamber tangentially to the inner surface of the chamber and upwardly or outwardly toward the exit of the nozzle.

With the above and other objects to appear hereinafter, my invention consists in the novel features of construction and in the arrangement and combination of parts to be hereinafter described and more particularly pointed out in the subjoined claims.

In the drawing:

Fig. 1 is a side elevation of a spraying nozzle constructed in accordance with my invention and supported by means of a supporting spike entered into the ground, the nozzle having a laterally-projecting inlet-nipple and a hose connected to said nipple.

Fig. 2 is a central longitudinal section through a nozzle provided with an inlet opening at its lower end.

Fig. 3 is a plan view of the nozzle shown in Fig. 2.

Fig. 4 is a central longitudinal section through a nozzle similar to that shown in Fig. 2, with the exception that its concentrating stud is shown longer and of smaller diameter than the concentrating stud illustrated in Fig. 2.

Fig. 5 is a side elevation of the swirler element.

Fig. 6 is a cross section taken on line 6—6, Fig. 5.

Figs. 7 and 8 are vertical sections through the swirler element, shown in modified form.

5 Fig. 9 is a central vertical section of a spraying head or nozzle slightly modified in exterior contour to adapt it for use as an inset nozzle for lawns.

10 Fig. 10 is a central vertical section of an inset sprayer head or nozzle of further modified construction.

Fig. 11 is a cross section taken on line 11—11, Fig. 10.

15 The drawing illustrates my invention in different forms of use, Fig. 1 showing a supported nozzle adapted to be positioned above the surface of a lawn and to have attached thereto a common garden hose.

20 Figs. 2 to 4, inclusive, show the nozzle adapted for hand spraying, particularly for spraying trees, shrubbery, and plants of various kinds, the nozzle being designed for attachment to a pipe or a hose.

25 Figs. 9 and 10 illustrate my invention in forms adapted for use in connection with underground water pipes, to which they are to be attached and positioned flush, or substantially flush, with the surface of a lawn.

30 My improved nozzle comprises a nozzle head having a casing 13 provided with a liquid inlet opening 14 and a spray outlet or exit opening 15.

35 In Fig. 1 the casing is provided with a lateral inlet nipple 16 internally tapped to form the inlet opening and to receive the threaded end of a garden hose 17. The casing also has a spike 18 projecting from its lower end, which is adapted to be thrust into the ground to support the nozzle at the desired elevation above the lawn.

40 In Figs. 2 and 4, the liquid inlet opening 14 is at the lower end of the casing co-axial with the outlet or exit opening 15, said inlet opening being tapped, as shown, for connection thereto of the threaded end of a pipe or hose, in a manner similar to that shown in Fig. 1.

45 Above the threaded inlet opening 14, the nozzle is interiorly enlarged, as at 19, to form a pressure chamber, and it is provided with a reduced portion 20 adjacent said enlarged portion or pressure chamber to form a seat for the swirler element 21. The reduced portion 20 is of a diameter somewhat less than the minimum diameter of the screw-threaded inlet opening 14, and from the reduced portion to the exit opening the interior of the casing 13 is gradually reduced, forming a discharge chamber 22; a shoulder 23 being provided 50 between the gradually reduced wall of the casing and the cylindrical wall of the seat 20.

55 While the circular or peripheral wall of the exit chamber 22 is shown internally concaved, this wall may be straight lined from the shoulder 23 to the exit opening 15, as shown, for example, in Fig. 9, but in either case the wall may be termed a dome wall and be said to taper from the shoulder 23 to said exit opening. The cylindrical wall of the seat 20 and the shoulder 23, which may be considered as part of said seat, are machined smooth and even. The screw threads are preferably machined and the exit opening 15 rendered smooth by machining, or otherwise forming the same. The remaining interior surfaces of the casing may be left in the form in which they are cast. It is particularly to be noted that the diameter of the seat 20, in addition to being smaller than that of the minimum diameter of the screw-threaded inlet opening 14, is considerably greater 60 than the diameter of the exit opening 15.

The swirler element 21 is formed of sheet brass or other suitable material stamped or otherwise fashioned into substantially cup-like formation to form a bottom 24, and a peripheral wall 25, the upper or outer end thereof being open its full extent. Axially disposed within this swirler element or cup-like member is a concentrating stud 26, it being shown in different lengths, different diameters, and different forms in several figures of the drawings. In each instance this stud is shown provided at its lower or inner end with an axial nub which is passed through an opening in the bottom of the cup-like member and headed against the under side of said bottom. Other means may, however, be employed for fastening said concentrator stud in position. In Fig. 2 I have shown the concentrating stud terminating at its upper end within the cup-like member. In Fig. 4 it is shown of a length to project above the upper edge of the cylindrical wall of the cup-like member and it is of somewhat smaller diameter than the concentrating stud shown in Fig. 2.

90 In Fig. 7 the stud is gradually enlarged in diameter from its lower or inner end to its upper end. In Fig. 8 it is gradually enlarged from its lower or inner end to a plane a short distance from its upper end and from said plane is made cylindrical to its upper end. The purposes of these variations in form will be hereinafter referred to.

95 The peripheral wall of the swirler element 21 is provided with inlet ports 27 formed by slitting the wall longitudinally and bulging the metal forming the wall inwardly at one side of the slit from the bottom 24 upwardly so as to form external grooves 28 in the inwardly-bulged metal portions which extend from the true periphery of the swirler element inwardly tangentially to the inner surface of said peripheral wall, the 110 grooves being gradually widened and deepened inwardly and being directed or inclined upwardly.

100 The inlet ports thus formed admit liquid under pressure into the swirler element, the interior of which may be referred to as a swirler or rotation chamber, for the reason that the inwardly-bulged tangentially-disposed portions of the wall direct the liquid passing through these ports or openings against the peripheral wall of the swirler element in tangential lines so as to compel 115 it to travel in a circular path and have component therewith movement upwardly or toward the open end of said swirler element. The liquid entering each port is therefore directed in a circular path and upwardly or outwardly 120 so that it passes over the inwardly-projecting wall-portion of the port or ports in advance. In other words, the water may be said to take a 125 helical course through the swirler element.

130 The concentrating stud 26 disposed axially within the swirler element provides an annular space or passage 28 around said stud surrounded by the peripheral wall of the cup-like swirler element, and this space or passage approximates the combined area of the ports in said swirler element; thus in no manner varying the pressure 135 of the liquid, as it passes through the swirler element, from that under which it enters said element.

140 In some instances where the pressure is exceedingly high and the extent of projection of the liquid from the nozzle and the area which it is intended to cover does not demand such high pressure, the concentrating stud 25 may be increased in diameter so as to diminish the an- 145

150

nular space or passage between the stud and the peripheral wall of the cup-like swirler element. This would somewhat reduce the pressure of the liquid in said swirler element from the point of entrance through the ports and consequently restrict the degree of projection of the liquid and the spread of the same as it escapes through the exit opening 15 of the nozzle.

It is to be noted that as the liquid escapes from the swirler element 21 it enters the gradually restricted discharge chamber 22, and in coming in contact with the tapering dome wall thereof is directed crosswise out of the exit opening; that is to say, the liquid coming in contact with the dome wall of the chamber 22 would be directed toward the axis of the sprayer head from all points in the circumference thereof and cause a commingling of cross currents, finally escaping through the exit opening 15 in spray form, as is common in spraying nozzles.

The circular course of the liquid through the swirler element with its component upward or outward movement eliminates friction to a considerable degree, and this results in the liquid being maintained in its course through the swirler element and the outer end of the nozzle casing under substantially the same pressure at which it enters the swirler element, resulting in a greater area being covered with the liquid under a given pressure than would otherwise be possible. The extent of projection of the liquid is thereby greatly increased; this being due to the fact that the inwardly-bulged portions of the peripheral wall of the swirler element, which may be referred to as port or liquid-directing walls are so formed that the water enters the swirler space or passage tangentially and moves upwardly or outwardly while traveling through a circular course so that it travels over the port or liquid-directing wall directly in advance.

The preferred arrangement under which I employ my invention is one in which the annular swirler space or passage is of uniform width from the point of admission at the inlet ports to the upper edge or end of the peripheral wall of said swirler element.

It is to be noted that the cup-like swirler element is non-rotatably arranged within the sprayer head or casing 13; it being firmly pressed or otherwise fastened in the seat 20 provided in said head or casing; also that the peripheral surface of the axially-disposed concentrating stud 26 and the inner surface of the peripheral wall of the swirler element, under which term I include the inwardly-bulged port walls, may be referred to as directional means.

Where it is desired to reduce the volume of water inside of the swirler element, I employ a stud which is gradually enlarged upwardly or outwardly, as clearly shown at 29, Fig. 7, or a stud, such as shown in Fig. 8, may be employed, wherein the stud is gradually enlarged upwardly or outwardly from its inner end to a point near its outer end and its formation lengthwise from said point changed to its outer end, preferably by forming the same cylindrical. A stud of this kind has decided advantages where the combined area of the inlet ports is less than the maximum dimension of the swirler space or passage between the stud and the peripheral wall of said swirler element; the greatest restriction occurring in line with the upper edge of the cup-like swirler element, which would advantageously be arranged so that it would approximate the combined area of the inlet ports. Under such con-

ditions, studs gradually enlarged outwardly would increase the circular or spiral travel speed of the liquid to that approximating the velocity of the liquid at the entering ports.

In its broader aspect, my improved swirler element may be employed without the use of the center concentrating stud, since under certain conditions effective spraying may be accomplished. There would, however, be a larger volume of liquid to rotate within the swirler element and the flow of the liquid would be retarded to some extent. The employment of the stud therefore is of advantage, but not absolutely necessary.

In the construction disclosed in Fig. 9, the sprayer head or casing 13 is enlarged considerably in diameter over that of the screw-threaded inlet opening 14 therein in which a water pipe 31 is fitted; the water pipe being one extremity of an underground water pipe system, and the head being fastened thereto with its upper or outer end slightly above the level of the ground. The head thus employed is what may be termed an inset head of the kind embedded in the ground and spaced apart over a lawn area. In this instance the head is provided with a flange 32 at its upper end having a downwardly-directed marginal rib 33 adapted to enter the soil, and openings 34 at diametrically opposite points for engagement therewith of a suitable tool for screw-threadingly fastening the head to the pipe 31.

The discharge chamber 22 of the nozzle is gradually restricted by having the inner surface of its dome wall straight-lined instead of concaved, as described in the preceding figures.

In the construction illustrated in Figs. 10 and 11, the sprayer head or casing 13 comprises two members 35, 36, one pressed into the other. I term member 35 the outer member, and it has an axial opening extending from end to end thereof; the inner member 36 being in the main of cylindrical formation and having its outer end portion pressed into the outer member 35 so as to be immovably joined thereto. Said members may, however, be otherwise connected together. The inner member has its peripheral wall curved inwardly at its outer end to form a stop flange 37 and its inner end is externally screw-threaded, as at 38, and entered into one end of a fitting 39 applied to the underground pipe, such as 31.

Vertically slidably in said inner member is a swirler or cage support 40, which is in the form of a bar of smaller diameter than the interior of said inner member and has at its inner end an enlargement 41; said enlargement being provided with diametrically opposite longitudinal grooves 42 into which are entered longitudinal internal ribs 43 pressed inwardly from the wall of said inner member, said ribs occupying only a portion of said grooves 42 so that liquid may pass from beneath said enlargement through said grooves and enter the space above said enlargement. The cage or swirler element 21 is mounted on the support 40, which serves as a plunger, and it is therefore movable with said support or plunger. Such movement is, however, limited to longitudinal movement since the rib and groove connection between the head or casing and the sprayer support or plunger prevent rotation of the latter. Over the open end of said swirler element 21, a deflector hood 44 is arranged, it being internally shouldered to bear against the upper edge of the peripheral wall of said swirler element and portions thereof being extended over the peripheral wall and tightly pressed thereon. This spreader hood has tapered upper wall portions provided

with an exit opening 45 at its upper end; said wall portions serving as a dome wall for the discharge chamber formed thereby, in the same manner as the dome wall of the constructions 5 hereinbefore described.

The swirler element is secured to the support or plunger 40 by means of a stud 46 having a reduced lower end 47 which is passed through the bottom wall of said swirler element and threaded 10 into said support or plunger, a shoulder formed by the reduced lower end of said stud bearing against the inner surface of said bottom wall.

At the upper end of the stud 46 a spreader head 48 is provided, it being preferably formed integral 15 with said stud, and its outwardly-flaring sides being adapted to normally rest against the upper edge of the outer member 35 of the sprayer casing, thus preventing any dirt entering said casing. When the parts are in normal position, the 20 support or plunger 40 with its spreader head 48, the cage or swirler 21, and the deflector hood 44 are lowered; the limit of its downward movement being controlled by said spreader head. When the water or other liquid under pressure is forced 25 upwardly against the support or plunger 40, the parts mentioned rise into the position shown in Fig. 11, the dome wall of the deflector hood or discharge chamber being in contact with and stopped by the stop flange 37 of the inner member 36 of the sprayer head or casing. The water or 30 other liquid enters the inlet 14 and passes through the grooves 42 in the enlargement of said support or plunger into the space surrounding the upper portion of said support or plunger and the swirler element. It then enters said swirler element through the ports thereof and is directed upwardly against the substantially tapering or dome 35 wall of the deflector hood, escaping therefrom and striking the flaring surface of the spreader head 48. Under this arrangement the water or other 40 liquid escapes through the outlet 15 formed by the annular space between the upper edge of the wall of the sprayer head or casing and the flaring wall of said spreader head in spray form.

45 It will be apparent from the foregoing, and the descriptions of the several modifications, all falling within the scope of my invention, as particularly set out in the appended claims, that various 50 changes in construction and arrangement of parts may be resorted to without departing from the spirit of my invention or sacrificing any of the advantages thereof.

Having thus described my invention, what I 55 claim is:

55 1. A spraying nozzle, comprising a casing having a tapped inlet opening at one end adapted for connection of a liquid supplying element thereto, an exit opening at its other end, and a pressure chamber between its ends, a swirler element open at one end and closed at its other end and comprising a cylindrical wall and a bottom wall, said swirler element having its closed end projecting into said pressure chamber and the cylindrical wall thereof being slit and having the metal thereof at one side of said slit bulged inwardly to provide a liquid-directing wall entering the interior of the swirler element and forming an inlet opening wholly within said cylindrical wall.

70 2. A spraying nozzle, comprising a casing having inlet and exit openings, and a non-rotatable swirler element within said casing of cup-like formation having its open end opening toward said exit opening and its closed end surrounded by space within said casing in communication

with said inlet opening, the peripheral wall of said swirler element being slit at intervals around the same and having the metal at corresponding sides of the slits bulged inwardly to form ports wholly within said swirler element and tangentially-disposed liquid-directing grooves leading to said ports, said grooves directing the liquid entering said ports against the inner surface of said peripheral wall tangentially thereto. 80

3. A spraying nozzle, comprising a casing having inlet and exit openings, and a non-rotatable swirler element within said casing of cup-like formation having its open end opening toward said exit opening and its closed end surrounded by space within said casing in communication with said inlet opening, the peripheral wall of said swirler element being slit at intervals around the same and having the metal at corresponding sides of the slits bulged inwardly to form tangentially-disposed upwardly-inclined grooves and liquid ports wholly within said swirler element to which said grooves lead, said grooves directing the liquid entering said ports against the inner surface of said peripheral wall and upwardly to cause the liquid to travel in a spiral course from 100 said ports towards said exit opening.

4. A spraying nozzle, comprising a casing having a comparatively large inlet opening and a small exit opening and having a pressure chamber between said openings and a discharge 105 chamber adjacent said exit opening, the wall of said casing having a cylindrical finished portion between said pressure chamber and discharge chamber provided with a downwardly facing shoulder at the upper end of said cylindrical 110 finished portion, a cylindrical cup-like swirler element of smaller diameter than said inlet opening inserted into said casing through said inlet opening and having its upper open portion pressed against said cylindrical finished portion and the shoulder thereof and having its closed lower end projecting into said pressure chamber, the projecting cylindrical wall of said swirler 115 element being provided with ports connecting the 120 interior of said swirler element with said pressure chamber, and a concentrating stud axially secured to the bottom wall of said swirler element to provide a circular space between the same and said cylindrical wall. 125

5. A spraying nozzle, comprising a casing having an inlet opening at one end adapted for connection thereto of a liquid-supplying element, an exit opening at its other end and a swirler within the casing open at its outer end and 130 closed at its inner end and including in its construction a peripheral wall, said swirler having at least a portion thereof spaced from the wall of the casing and having its peripheral wall slit and the metal thereof at one side of said slit bulged inwardly to provide tangentially disposed liquid-directing grooves, and ports at the inner end of said grooves wholly within the confines of said peripheral wall. 135

6. A spraying nozzle, comprising a casing having an inlet at its inner end, an opening at its outer end and longitudinal internal ribs between its ends, a swirler support slideable in said casing having an enlargement provided with longitudinal grooves into which said internal ribs extend to occupy only a portion of said grooves so that liquid may pass through said enlargement to the portion of the casing therebeyond, a swirler element secured axially to the outer end of said 145 150

swirler support and having its peripheral wall spaced from the wall of said casing, said swirler element having an exit opening at its outer end and said casing having a deflector hood near 5 its outer end against which said swirler is adapted to be forced under pressure of the liquid passed

therethrough, said swirler having inlet openings in its peripheral wall, and a stud arranged centrally within said swirler and having a spreader head at its outer end adapted to open or close 80 said first-mentioned opening.
